United States Patent Office

Des. 197,161
Patented Dec. 17, 1963

197,161

AMPOULE APPLICATOR

Walter K. Blumenstein, Fairview Park, and Anthony David, Cleveland, Ohio, assignors to The Otto Koniglow Mfg. Company, Cleveland, Ohio

Filed Sept. 6, 1962, Ser. No. 71,574

Term of patent 14 years

(Cl. D83—12)

I claim:

The ornamental design for an ampoule applicator, substantially as shown and described.
